Primary Examiner — Christian P. McLean*Assistant Examiner* — Kristopher Michael Blechschmidt(74) *Attorney, Agent, or Firm* — Gurr Branded & Spendlove, PLLC; Robert A. Gurr(57) **CLAIM**

The ornamental design for a flexible sleeve for decoys, as shown and described.

DESCRIPTION

FIG. 1 is a top, side perspective view of the flexible sleeve for decoys coupled to a decoy;

FIG. 2 is a rear, side perspective view of the flexible sleeve for decoys;

FIG. 3 is a right side elevation view of the flexible sleeve for decoys, the left side being a mirror image thereof;

FIG. 4 is a front elevation view of the flexible sleeve for decoys; and,

FIG. 5 is a rear elevation view of the flexible sleeve for decoys.

The broken lines shown in FIG. 1 are for the purpose of illustrating environmental matter that forms no part of the claimed design.

1 Claim, 2 Drawing Sheets(56)
